MULTIUSE READING TABLE

Charles W. McNair, Jacksonville, Fla., assignor
of one-half to B. D. Fincannon, Jacksonville,
Fla.

Application September 12, 1934, Serial No. 743,756

7 Claims. (Cl. 311—3)

My invention relates to a multi-use table.

The object of my invention is to provide, in a manner as hereinafter set forth, a table-structure capable of being selectively used as a bed table and as a floor table.

A further object of my invention is to provide, in a manner as hereinafter set forth, a table-structure capable of being employed as a screen.

A further object of my invention is to provide, in a manner as hereinafter set forth, a table-structure capable of being supported upon a bed for holding reading matter at an inclination and at a point with respect to the occupant of the bed to enable the occupant to conveniently see such matter without discomfiture.

A further object of my invention is to provide, in a manner as hereinafter set forth, a table-structure capable of being supported upon a bed and including means to constitute a food supporting tray and an adjustable book support for reading purposes.

A further object of my invention is to provide, in a manner as hereinafter set forth, a table-structure capable of being supported upon the floor and including means to constitute a food supporting tray and an adjustable book support for reading purposes.

A further object of my invention is to provide, in a manner as hereinafter set forth, an adjustable table-structure capable of providing a food supporting tray and an adjustable reading table for association with a chair, stool, bench, etc., or for mounting in superimposed position upon a bed in a convenient position for the occupant of the bed.

A further object of my invention is to provide, in a manner as hereinafter set forth, a table-structure including an adjustable, extendible, hinged structure providing, when adjusted and extended, an inclined support for reading matter, music, drawings, pictures, etc., and when not adjusted and extended, a horizontal support for food or other articles.

Further objects of my invention are to provide, in a manner as hereinafter set forth, a table-structure for the purpose referred to which is comparatively simple in its construction and arrangement, strong, durable, compact, readily adjustable for the several purposes for which it is designed, thoroughly efficient in its use, conveniently collapsed, and comparatively inexpensive to manufacture.

To the above ends essentially, and to others which may hereinafter appear, the invention consists of such parts, and such combination of

parts which fall within the scope of the invention as claimed.

In the drawings:

Figure 1 is a plan view of the multi-use table in accordance with my invention,

5

Figure 2 is a front elevation thereof,

Figure 3 is a section on line 3—3 Figure 1,

Figure 4 is a section on line 4—4 Figure 1, showing the extendible element in full lines in non-extended position and in dotted lines in extended 10 position.

Figure 5 is a fragmentary view in end elevation,

Figure 6 is a fragmentary view in section showing the form of detachable holdfast means 15 for the support for the extendible element, and

Figure 7 is a fragmentary view in front elevation illustrating the elements shown in Figure 6.

The table structure includes a body section, an adjustable, extendible section or element and a front or supporting section designated 8, 9, and 10 respectively.

The body section 8 includes a pair of spaced parallel side bars 11, each provided in proximity to one end thereof with a threaded opening 12 25 extending from the bottom to the top of the bar.

The openings 12 are arranged in alignment. Secured to the inner side face of each bar is a pair of spaced pivots 13, 14. The pivots on one bar align with the pivots on the other bar. The pivots 30 13 are arranged adjacent the front end and the pivots 14 positioned in proximity to the rear end of the bars. Mounted on the pivots 13 is a pair of foldable front legs 15. Mounted on the pivots 14 is a pair of foldable front legs 16. The legs 35 15 fold towards the legs 16. The legs 15, 16 when extended are adapted to support body section 8 upon a bed. Each bar 11 is formed in its outer end edge 17 (Figures 6 and 7) with a socket 18 disposed lengthwise of the bar. Abutting the end 40 edge 17 of each bar 11 is an outwardly directed suspension bracket 19 formed with a hollow arm 20 and a tubular interiorly threaded shank 21.

The arm 20 provides an inverted U-shape groove 22 open at each end and having its top wall in 45 the form of an arc. The outer side of arm 20 is bifurcated, as at 23. The shank 21 extends rearwardly from the inner side of arm 20 and snugly engages the wall of socket 18. The inner wall of arm 20 is formed with an opening 24 registering 50 with the inner face of the shank. The bracket 19 is formed with a pair of inwardly extending flanges 25 which abut the side faces of and are secured to the bar by holdfast means 26.

The section or element 9 includes a pair of flat 55

flanges 27 which abut the side faces of and are secured to the bar by holdfast means 28.

oblong side members 27 arranged in superposed spaced relation with respect to the bars 11. Spacing means 28 is interposed between the rear of members 27 and the bars 11. A pair of spaced 5 parallel strap hinges 29 (Figures 4 and 6) are arranged upon the upper faces of the bars 11. Each hinge includes a pintle 30 and an upper and a lower leaf 31, 32 respectively. The barrels 33 on one end of each of the leaves of a hinge are flush 10 with the front end edge of a bar 11. The lower leaves of the hinges are anchored upon the upper faces of the bars 11. The upper leaves of the hinges are anchored to the lower faces of the side members 27. Holdfast means for anchoring the 15 leaves of the hinges stationary are indicated at 34.

Secured upon the side members 27 and extending outwardly and rearwardly therefrom is a plate 35 of any suitable material constituting a support. Secured to and depending from plate 35 is a pair 20 of spaced oppositely disposed combined guide and track members 36 of angle shape cross section. Each member 36 is interposed between the transverse median of plate 35 and a side of the latter. Interposed between the members 27 and 36, 25 as well as being secured to said members and to plate 35 are spaced braces 37. The members 36 have their outer ends flush with the outer edge and their inner ends spaced from the rear edge of plate 35. Interposed between, as well as being secured to the member 27, is a brace 38. The latter abuts the inner ends of the members 36 and is secured to plate 35. Mounted upon the marginal portion of the upper face of plate 35 at each side of the latter, is a ledge forming strip 39. 30 Mounted on each end of the marginal portion of the upper face of the plate 35 at the front of the latter is a short ledge forming strip 40. These latter provide continuations and are of the same contour as the strips 39. The free ends of the strips 40 are oppositely beveled as at 41. The strips 40 are arranged in spaced relation to provide a gap 42 which is closed by a means to be referred to.

Slidably supported by the members 36 is an extendible member 43 in the form of a flat board provided at its transverse center with a slot 44 having its walls reinforced by a thin slotted metallic strip 45. The edges of the slots in strip 45 are flush with the walls of slot 44. The strip is countersunk in and anchored to member 43. The latter has the marginal portion of its upper face at the front thereof provided with a ledge forming strip 46 of the same contour as the strips 39 and 40. The strip 46 is employed for closing the gap 42 when the member 43 is in non-extended position. The ends of strip 46 are oppositely beveled.

The member 43 is adapted to be extended from the front of the plate 35, and when so extended it is detachably held in such position by a binding device (Figures 2 and 4) consisting of a screw 47 countersunk in and depending from plate 35 through slot 44 and strip 45. Carried by screw 47 is a washer 48 arranged in slot 44. Mounted on screw 47 is a wing nut 49 adapted to be adjusted to bind against strip 45 whereby member 43 will be clamped from movement and retained in its adjusted position. The binding device also acts to clamp member 43 from movement when the latter is non-extended. Secured to the brace 38 and depending therefrom is a handle member 50 for raising section 9 on the hinges 29 for moving section 9 to and from tilted or inclined position, the inclined position of section 9 being illustrated in dotted lines, Figure 4. After section

9 has been tilted or inclined with respect to section 8, the member 43 is adjusted to extend from plate 35 to the dotted position shown in Figure 4. The section 9, when the member 43 thereof is not extended, provides a support for foods or other articles. When section 9 has been tilted and member 43 adjusted the latter provides a support for matter to be read or examined. 5

Secured to the rear edge of plate 35, as well as depending from the latter are a pair of spaced 10 concealing members 51.

The section 9 is supported in tilted or inclined position by a latchable supporting structure 52 arranged at each side thereof and also at each side of section 8. The structure 52 includes a pair 15 of links 53, 54, the former being pivoted at its rear end, as at 55 to a side member 27. The link 54 is pivoted at its rear end, as at 56 to bar 11. The forward ends of links 53, 54, are pivotally connected at 57. The structure 52 also includes a 20 latching and bracing member 58 of link like form having its upper end loosely mounted on pivot 57. The lower end of member 58 is formed with a T-shape notch, as at 59 for selectively engaging with a series of spaced parallel headed pins 60 25 secured to a bar 11. When the section 9 is shifted on the hinges 29 to an inclined position the links 53, 54 are extended relatively to each other and member 58 connected to a pin 60 whereby said links are held in extended position to arrest 30 the shifting of section 9 forwardly or rearwardly. The pins 60 in connection with member 58 and structure 52 provide for maintaining the section 9 in various angular positions with respect to section 8. The member 58 when not in use is dis- 35 posed along the side of structure 52.

The section 9 is detachably held in horizontal position by a pair of sectional latching devices 61 (Figure 5). The latching devices are arranged at the sides of sections 8, 9 and each consists of 40 a male and a female member 62, 63. The construction of said members is to provide for member 62 frictionally engaging within member 63. The member 62 is anchored to a bar 11 and member 63 to a side member 27. 45

The section 10 is of substantially dumb-bell contour and includes a pair of thin flat circular members 64 constituting supports for articles and a combined coupling and supporting bar 65 common to said members 64. The end portions 66 of 50 bar 65 are squared and extend diametrically of the lower faces of and are anchored to the members 64. Secured against the lower face of each member 64, abutting the sides of and disposed at right angles to the end portion 66 of bar 65 is 55 a pair of oppositely extending braces 67, 68 each carrying an interiorly threaded socket former 68. The bar 65 is formed with a pair of spaced stretches 69 of circular cross sections. A squared end portion 66 merges into the outer end of a 60 stretch 69. The bar 65 is also formed with an elongated beveled stretch 70, which at its ends merges into the inner ends of the stretches 69. The beveled stretch 70 provides a clearance and seat for the extension 43 when extended after the 65 section 9 has been moved to a tilted or inclined position. In this connection see dotted line showing Figure 4. Each stretch 69 is formed with a diametrically disposed opening 71. When section 10 is positioned relative to section 9, the brackets 70 75 overlap the stretches 69 (Figures 1, 2, 6 and 7). The section 10 is detachably connected to section 9 by the passage of wing headed bolts 72 through the openings 71 to threadedly engage in the shanks 22 of the brackets 19 (Figure 6). The 75

bolts 72 pass through the furcations formed in the outer sides of the arms 20 of the brackets 19.

The table-structure includes two pairs of legs. The legs of one pair are designated 13 and those of the other pair as 74. The legs 13, 74 are of greater length than the legs 14, 15. The legs 13 form a permanent part of the supporting section 10 and are secured in the threaded socket formers 68 carried by the braces 67. The legs 74 are selectively associated with the sections 8 and 10, and when used in connection with section 8 they are connected to the bars 11 through the medium of the threaded walls of the openings 12 engaging with the threaded upper terminals 75 of the legs 74. When these latter are used in connection with section 10 they are connected to the threaded socket formers 68 carried by the braces 67.

The supporting section 10 is arranged relative to section 8 to permit of the convenient separation of section 10 therefrom whereby sections 8, 9 may be utilized as a bed table for supporting food or for supporting reading or other matter. When so used the legs 14 are not connected to section 8, but the legs 15, 16 are extended to rest upon the bed to support sections 8 and 9. When sections 8, 9 and 10 are used together to provide a floor table, the legs 15, 16 are not extended, but the legs 74 are secured to the bars 11 and contact with the legs 13 for supporting sections 8, 9 and 10 from the floor. When employed as a floor table section 9 may be extended and adjusted for supporting reading or other matter at an inclination.

The brackets 19 provide a suspension for sections 8, 9 when the table-structure is employed as a screen. In this connection the bolts 72 are removed and the section 8 swings downwardly on the stretches 69 whereby brackets 19 will act as a suspension. To prevent the separation of the sections 8, 9 from section 10, when the table-structure is employed as a screen, the end portions 66 of bar 65 have attached thereto flexible members 76, provided with hooks 77 for detachable engagement with eyes 78, extended laterally from the side members 27.

What I claim is:

1. In a multi-use table, a body section, foldable legs pivoted to the latter, an angularly adjustable section arranged over, and hinged at its front to, said body section, said adjustable section carrying a slidable extension member and being provided with means for detachably securing said extension member in extended and non-extended position, and said adjustable section having a ledge secured thereto on its upper face, a portion of the ledge being carried by said extension member.

2. In a multi-use table, a front section, a supporting structure connected thereto and extended rearwardly therefrom, an adjustable superstructure arranged over the supporting structure and including an extendible support for extension over said front section, said front section being formed with a clearance for said support when the latter is extended, means for hinging the superstructure to the supporting structure to provide for the adjusting of the superstructure, means for latching said structures together, and

legs connected to said front section and supporting structure.

3. In a multi-use table, a front section, a supporting structure connected thereto and extended rearwardly therefrom, an adjustable superstructure arranged over the supporting structure and including an extendible support for extension over said front section, said front section being formed with a clearance for said support when the latter is extended, means for hinging the superstructure to the supporting structure to provide for the adjusting of the superstructure, means for latching said structures together, legs connected to said front section and supporting structure, and means for supporting said superstructure in adjusted position.

4. In a multi-use table, a front section, a supporting structure connected thereto and extended rearwardly therefrom, an adjustable superstructure arranged over the supporting structure and including an extendible support for extension over said front section, said front section being formed with a clearance for said support when the latter is extended, means for hinging the superstructure to the supporting structure to provide for the adjusting of the superstructure, means for latching said structures together, and legs connected to said front section and supporting structure.

5. In a multi-use table, a front section, a supporting structure connected thereto and extended rearwardly therefrom, an adjustable superstructure arranged over the supporting structure and including an extendible support for extension over said front section, said front section being formed with a clearance for said support when the latter is extended, means for hinging the superstructure to the supporting structure to provide for the adjusting of the superstructure, means for latching said structures together, and legs connected to said front section and supporting structure.

6. In a multi-use table, a front section substantially of dumbbell contour, a supporting structure having means at its front for coupling it at spaced points to said section intermediate the ends of the latter, an adjustable superstructure arranged over the supporting structure, means for hinging said structures together at the front thereof, means for latching said structures together, and supporting legs attached to said section and supporting structure.

7. In a multi-use table, a front section substantially of dumbbell contour, a supporting structure having means at its front for coupling it at spaced points to said section intermediate the ends of the latter, an adjustable superstructure arranged over the supporting structure, means for hinging said structures together at the front thereof, means for latching said structures together, supporting legs attached to said section and supporting structure, said superstructure including an extendible support, and said front section having means intermediate its ends to provide a combined clearance and seat for said support when the latter is extended.

CHARLES W. McNAIR.
